(57) **CLAIM**

The ornamental design for a hospital screen, as shown and described.

DESCRIPTION

FIG. 1 is a bottom plan view of the trolley mounted hospital screen of the present invention in the bent position;

FIG. 2 is a bottom plan view thereof in the folded position;
FIG. 3 is a cross-sectional view thereof in the bent position;
FIG. 4 is an elevation view of the back thereof in the folded position;
FIG. 5 is an elevation view of the front thereof in the folded position;
FIG. 6 is an isometric view of the right side thereof in the bent position;
FIG. 7 is an isometric view of the back thereof in the folded position;
FIG. 8 is an isometric view of the left side thereof in the bent position;
FIG. 9 is an isometric view of the front thereof in the folded position;
FIG. 10 is a top plan view thereof in the bent position;
FIG. 11 is a top plan view thereof in the folded position;
FIG. 12 is an elevation view of the right side thereof in the bent position;
FIG. 13 is an elevation view of the left side thereof in the folded position;
FIG. 14 is an elevation view of the right side thereof;
FIG. 15 is a bottom plan view thereof in the extended position;
FIG. 16 is an elevation view of the back thereof in the extended position;
FIG. 17 is an elevation view of the front thereof in the extended position;
FIG. 18 is an elevation view of the right side thereof in the extended position;
FIG. 19 is an elevation view of the left side thereof in the extended position;
FIG. 20 is an elevation view of the left side thereof in the extended position;
FIG. 21 is a top plan view thereof in the extended position;
FIG. 22 is an elevation view of the thereof in the extended position; and,
FIG. 23 is an elevation view of the right side thereof in the extended position.
